COUNTING DIAL

John J. Arnold, Whitewater, and Harold G. Foote, Fontana, Wis., assignors to Amphenol-Borg Electronics Corporation, Broadview, Ill., a corporation of Delaware

Filed Mar. 2, 1962, Ser. No. 69,054

Term of patent 14 years

(Cl. D52—1)

FIG. 5

FIG. 1 is a perspective view of a counting dial, including a brake applying ring, showing one embodiment of our new design;

FIG. 2 is a side elevational view thereof;

FIG. 3 is a front elevational view thereof;

FIG. 4 is a rear elevational view thereof;

FIG. 5 is a perspective view of another embodiment of our new design, similar to that shown in FIG. 1, but with the brake applying ring omitted;

FIG. 6 is a side elevational view of the modified form shown in FIG. 5;

FIG. 7 is a front elevational view of FIG. 5; and

FIG. 8 is a rear elevational view of FIG. 5.

The essential features of the design are shown in full lines.

We claim:

The ornamental design for a counting dial, as shown and described.
